ABSTRACT: An auger-type valve bag-filling machine having an electrical control circuit adapted to operate the auger to fill the bag until a predetermined, but less than the desired total, weight of product is reached, whereupon a timer circuit is energized which then maintains the auger in operation for a timed interval to complete filling of the bag.

BAG-FILLING MACHINE

The invention is directed to a bag-filling machine of a known type in which a dry product is conveyed from a hopper through a filling tube by a motor-driven auger to fill a valve-type bag with the product discharged through the filling tube. In a conventional machine of this type the bag support and the outer end of the filling tube are mounted on and movable with a scale beam, and when a desired weight of product is reached movement of the scale beam opens a limit switch which stops the auger to prevent further delivery of material to the bag.

The machine of the type described above has the serious disadvantage of requiring the use of unnecessarily large bags to receive a given amount of material. This disadvantage arises from the fact that the outer end of the filling tube, being movable with the bag and the scale beam when the predetermined weight is reached, must also move relative to the outer end of the auger which extends through such portion of the filling tube. If the bag size is selected so that it is just large enough to contain the required weight of material but no larger, bearing in mind that space must be provided for the end of the filling tube, then the last portion of product delivered to the bag will not be free-falling but in effect will cause a back pressure on the stream of product in the filling tube, causing the latter to run substantially full of product rather than less than completely full as is the case prior to the last stages of the filling operation. When the filling tube is substantially filled with product under these conditions, particularly if the product is under a slight back pressure, the required freedom of motion of the outer end of the filling tube relative to the auger is hindered since the product in effect mechanically couples the outer end of the filling tube to the auger. This condition prevents consistent accurate triggering of the weighing mechanism at the required weight. It is therefore common practice in machines of this type to use bags that are large enough to hold the desired weight without the product level reaching the level of the filling tube. This, of course, results in an additional expense for the larger bags that are used.

The present invention is directed to an electrical control circuit for a machine of the type described which embodies a timing circuit. According to the present invention the motor-driven auger is first energized through a more or less conventional circuit and the weighing mechanism is set to weigh the product and open a limit switch to deenergize such circuit when the product level is at a point below the normal fill height and while the material is still being discharged from the filling tube in a free-falling state, thus allowing the required free relative motion between the filling tube and auger at this time. The circuit includes a timer circuit which maintains the auger in operation for a timed interval which will complete filling of the bag to the required weight and then deenergize the auger. This enables the use of bags that are no larger than necessary to contain the desired amount of product, resulting in a substantial saving in cost as compared with the larger bags that are now required.

In the drawings:

FIG. 1 is an elevational view, partly in section, of a bag-filling machine of the kind to which the invention is directed; and

FIG. 2 is a circuit diagram illustrating the circuits for controlling operation of the machine.

In FIG. 1 the bag-filling machine is shown as comprising a frame 10 having a hopper 12 supported thereon and adapted to contain a supply of material 14 to be delivered to a valve-type bag 16. An auger 18 extends through the lower end of the hopper 12 and is driven by an electric motor 20 through belts 22 which extend around a drive pulley 24 and a drive pulley 26 which is secured on the outer end of the auger shaft 28.

At its lower end the hopper 12 is provided with a discharge spout 30 through which the auger 18 extends. A filling tube 32 forms a continuation of the spout 30 but is formed separately therefrom and is spaced from the outer end of the spout 30 by a narrow gap 34. The filling tube 32 is mounted on a hanger rod 36 which is secured to the end 38 of a scale beam 40 which is pivotally or otherwise movably mounted on the frame 75

10 of the machine. The lower end of the hanger rod 36 is connected to the base 10 by a link 42. The scale beam 40 is provided with a weight 44 which may be adjusted to set the weighing mechanism to trip at a predetermined weight. A bag support 46 extends laterally from and is secured to the hanger rod 36 and the bag 16 is adapted to be positioned on the bag support 46 with the filling tube 32 extending through a valve opening at the upper end of the bag.

In a machine of this type the filling tube 32 is customarily only about three-quarters full of the material being conveyed therethrough by the auger in order to allow the required freedom of movement of the tube relative to the auger when a predetermined weight of material is reached. As long as the material is in a free-falling state as it is discharged from the end of the filling tube, this freedom of motion between the tube and the auger will be present. However, it will be seen from FIG. 1 that if the weighing mechanism is set to trip the limit switch which controls the motor circuit only after the material fills the bag up to the level of the filling tube, that is, beyond the point at which the material is still falling freely from the end of the filling tube, the back pressure caused by the mass of material at the end of the tube will cause the tube to fill substantially completely with the material, thus preventing the required freedom of movement of the tube relative to the auger.

According to the present invention, the weighing mechanism may be set to trip the limit switch controlling the motor circuit while the material is still falling freely from the 30 end of the filling tube and the level of material in the bag is below the level to which it ultimately will be filled. The electrical circuit to accomplish such result is shown in FIG. 2. The circuit includes power leads 50, 52, and 54 which control operation of the reversible motor 20 in a conventional manner. A transformer 56 supplies power to the control circuit.

To initiate a cycle of operation the operator of the machine momentarily depresses a start button 58 which engages contacts 60 and contacts 61 to close a circuit through a starter coil 62, relay coil 64, and timing relay 66. Energizing of coil 62 closes the normally open switch 68 and opens the normally closed switch 70. Energization of timing coil 66 closes the normally open switch 72 and energization of coil 64 closes normally open switch 74 and opens normally closed switch 76. 45 When the start button 58 is released the relays 62 and 66 will remain energized through switch 68, normally closed switch 78, and stop switch 80, while the relay 64 will remain energized through switch 74 and the normally closed limit switch 82. The limit switch 82 is shown in FIG. 1 as having contacts 35 operable by the scale beam 40 so as to open the switch when the bag weight reaches a predetermined value.

Energizing of coil 62 will close the corresponding motor contacts 84 to operate the motor 20 in one direction to drive the auger and initiate the bag-filling operation.

When the weight of the product in the bag reaches a predetermined and adjustable value, the scale beam 40 will be tripped to open the limit switch 82, thereby deenergizing relay 64, opening switch 74, and closing switch 76. Closing of switch 76 energizes the relay 86 which is a timing relay which controls switch 78. The timing relays 66 and 86 may be of conventional or known construction. Coil 86 is designed to open switch 78 after a predetermined time interval following energization of coil 86, during which interval the motor coil 62 will remain energized to complete filling of the bag. As soon as switch 78 opens, the motor relay 62 and the timing relay 66 will be deenergized. Deenergization of relay 62 opens motor contacts 84 to stop operation of the motor and of the auger 18. The time interval between energization of relay 86 and opening of switch 78 is selected so that the amount of material delivered by the auger during this interval will fill the bag to its required level.

As soon as coil 62 is deenergized the normally closed switch 70 will close and switch 68 will open. At the same time deenergization of timing coil 66 will close the normally open

switch 72, thus establishing a circuit through the reverse motor coil 88 to close motor contacts 89 to reverse the direction of rotation of the auger 18. After a further predetermined time interval the switch 72 which is controlled by the timer relay 66 will open, thus deenergizing the coil 88 to stop the motor. A normally closed switch 90 responsive to motor coil 88 is disposed in the line between the motor coil 62 and the starting contacts to prevent accidental energization of coil 62 when the motor is in reverse operation.

At the end of the cycle of operation described, the bag is removed from the bag support and the scale beam 40 will return to the starting position to close the limit switch 82, and the machine is then ready for another cycle of operation.

The control circuit described has the advantage of enabling operation of the weighing mechanism at a time during the bag-filling operation when the required free relative movement between the filling tube and the auger can take place. The auger therefore continues the filling operation under timed control rather than by weight of the contents of the bag. In a machine of this type the quantity of product delivered per second by the auger is very consistent and the auger can very accurately fill the bag to the required level during the time interval.

What I claim as my invention is:

1. An auger-type bag-filling machine for filling a valve-type bag with a required weight of material, comprising a weighing mechanism responsive to the weight of material in the bag, an auger for conveying material through a valve opening in a bag to be filled, an electric motor for driving said auger, and an electrical circuit for said motor which when energized operates said motor to drive said auger and convey material into said bag, said circuit including a means actuated by said

weighing mechanism when the weight of material in the bag reaches a predetermined value less than said required weight to cause continued operation of said motor for a timed interval to fill the bag to the required weight and to open said circuit upon termination of said timed interval.

2. An auger-type bag-filling machine for filling a valve-type bag with a required weight of material, comprising a movable bag support, a weighing mechanism having a part thereof movable with said bag support, an auger for conveying material through a valve opening in a bag on said support, an electric motor for driving said auger, and an electrical circuit for said motor which when energized operates said motor to drive said auger and convey material into said bag, a switch in said circuit operable responsive to movement of said part of said weighing mechanism to open said circuit when the weight of material in the bag reaches a predetermined value less than said required weight, an auxiliary circuit for said motor adapted to be closed upon closing of said first circuit, a timing relay in said auxiliary circuit, operation of said switch being operable to energize said timing relay, said timing relay upon energization thereof being adapted to initiate a timed interval during which said motor remains energized through said auxiliary circuit to fill the bag to the required weight and to open said auxiliary circuit upon termination of said timed interval.

3. A machine according to claim 2 wherein said circuit includes means for operating said motor and auger in a reverse direction upon termination of said timed interval.

4. A machine according to claim 3 wherein said circuit includes means for terminating said reverse operation of said motor after a timed interval.
